PACKING SHEET

Paul A. Schilling, 2048 Lower St. Dennis Road, and
Thomas G. Mairs, 1707 Delaware Ave., both of St.
Paul, Minn.

Filed Apr. 20, 1959, Ser. No. 55,565

Term of patent 14 years

(Cl. D58—13)

FIG. 1

We claim:

The ornamental design for a packing sheet, as shown.
